SOUND RECORDING

David Pelton Moore, Avon Park, Fla., assignor to
General Talking Pictures Corporation, New
York, N. Y., a corporation of Delaware

Application December 15, 1932
Serial No. 647,443

6 Claims. (Cl. 179—100.3)

The present invention relates to improvements in sound recording and more particularly to recording sound-on-film to produce what is known in common parlance as "noiseless recording",

5 one object of the invention being the provision of an arrangement of glow lamp recording in which the present type of glow lamp recording system is utilized in combination with a novel arrangement of shutter, blinker or the like, which when 10 the microphone is inactive acts as a shield between the glow lamp and the film, but which under recording conditions permits the rays of light from the glow lamp to impinge upon the film to produce a sound track thereon of the 15 variable density type and by and in accordance with the sound to be recorded.

A further object of this invention is the provision of a sound recorder in which a novel arrangement of galvanometer control is used in 20 conjunction or in coordination with a recording lamp of the photon or glow type so that a normal luminosity of the lamp is maintained at all times and the lamp in the same close proximity as is the practice in recording systems of this type 25 at the present time, the galvanometer control means being so arranged that it is influenced due to the impinging of sound waves upon the microphone and simultaneously with the modulation of the glow lamp so as to permit the rays of light 30 from the glow lamp during the sound modulation thereof, to affect the moving sensitized film, thus producing an automatically controlled means which when the microphone is not having sound waves impinged thereon will cause a light excluding barrier to be interposed between the lamp and the film so that the sensitized film as a negative when developed will have an entirely clear 35 sound track, and which when barrier is open will permit the proper recording thereon in the usual 40 manner.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

Although several circuits may be employed to accomplish this result, there is illustrated and described in this particular case only one form but such form is clearly illustrative of the present 55 invention.

In the accompanying drawing:

Figure 1 is a diagrammatic view of a complete recording installation embodying the present invention.

Figure 2 is a diagrammatic view of an iris dia- 60 phragm shutter.

Figure 3 is a view of a modified form of shutter which displaces the iris diaphragm.

Referring to the drawing, and more particularly to Figures 1 and 2 thereof, the numeral 1 designates a microphone which is connected in the usual manner through conductors 2 and 3 to a first stage amplifier 4, which in turn is connected by conductors 5 and 6 to a second stage amplifier 7. Conductors 8 and 9 connect the output of the amplifier 7 to the input of a power amplifier 10, the output of which is connected to the glower recording lamp 11 through conductors 12 and 12', a stopping condenser 13 being interposed therein. A conductor 12" is connected 75 to conductor 12 and has a variable resistance 14. Conductors 15 and 17 are connected to the negative side of the battery 18 and the amplifier 10, conductors 19 and 19' being connected to the lamp 11 at the opposite side of the battery 18. 80 This much less the conductor 12 and variable resistance 14 constitutes in general a normal sound recording system. A galvanometer G is connected by conductor 19" to elements 14—14' 85 at one side and at the other side to the battery 18 through the conductor 19'. A coupling resistance 20 is employed as usual and with the variable resistance 14 controls the amount of direct current through the galvanometer. Conductors 21 and 22 are connected to the conductors 8 and 9 90 respectively and to an auxiliary power amplifier 23, the output of which is connected through the conductors 24 and 25, to a Wheatstone bridge rectifier network apparatus 26 with the stopping condenser 27 in the line. The power amplifier 23 is here shown in the form of an output transformer, the terminals of the secondary of which are connected to the points 28 and 29 of the network 26 whose remaining points 30 and 31 are connected respectively through the conductors 100 32 and 33 to the conductors 15' and 17 respectively. Connected in the line 32' and 33' and between the lines 32 and 33 is a large reservoir condenser 16 there being provided a ground connection at 27 and also a ground connection at 105 20'. A by-pass condenser 14' is also provided around the resistance 14.

This galvanometer as shown in Figure 2 is operably connected to the arm 40 of the iris dia- 110 phragm shutter 41 and as will presently appear,

when no sound is impinged upon the microphone will hold the shutter in closed position, but instantly upon the impinging of sound upon the microphone will be moved to open position so that 5 the rays of light from the terminals 42, 42' of the lamp 11 will be permitted to pass through the slit 43 and thus affect the sensitized film 44. This film as is usual in recording apparatus is carried by the respective supply reel 45 and take-up reel 10 46 and is operated by the film progressing mechanism or sprockets 47 and 48.

By this arrangement it will be noted that there is introduced in series with the galvanometer and the main supply battery 18 an additional source 15 of direct current, that is, through the medium of the large reservoir condenser 16. This is maintained charged at a fixed and desired polarity by means of the special rectifying network 26, the latter as shown consisting primarily of four rectifiers 36, 37, 38 and 39 arranged as indicated, and 20 in such a manner that the current from the output of the transformer 23 is delivered at the terminals 30 and 31 of the network and always flows in the same direction, regardless of the reversals of the voltage across the input terminals 28 and 29. Thus, by this bridged rectifier circuit arrangement the output energy from the amplifier 23 is at all times stored in the large reservoir condenser 16 with unchanging polarity but in varying 30 amounts at varying potentials. Thus, by the above circuit arrangement there is secured a variable additional source of E. M. F. in series with the battery 18, the amount of additional voltage being thereby introduced into the galvanometer supply circuit and is proportional to the amount 35 of energy coming from the auxiliary amplifier 23 which in turn is proportional to the amount of sound energy picked up by the microphone.

Thus when no sound is impressed upon the 40 microphone 1 the normal current passing through the galvanometer will have been such as to cause the shutter 41 to be held in closed position while the cathode 42 of the lamp 11 will be at all times subject to the same current effects, and as the 45 microphone is not being impinged by sound its rays are shut off through the shutter 41 so as to be ineffective upon the film. The impingement of the sound upon the microphone however will cause the galvanometer to be sufficiently energized to open the shutter 41 and thus permit the modulated light rays from the lamp 11 to impinge upon the moving film 44 and thus effect the same, so that, when developed, a variable density sound track will result with interspersed even 55 dense spaces.

It will thus be evident that with this system the negative film when developed will contain the sound track thereon in which the silent intervals due to the absolute closure of the shutter 41 will 60 be substantially transparent and will therefore print upon the positive when developed a constant or even black which when run through a sound reproducing machine will have no perceptible ground noise and to all intents and purposes 65 will produce silence where intended.

Thus there is added to the normal photion or glow lamp recording system an auxiliary device which renders the effect of the lamp upon the film negative during periods of silence, or when the 70 microphone is not being impinged, by sound, but instantly upon the impingement of sound upon the microphone will permit the rays of light from the photion or glow lamp to be recorded on the film by and in accordance with the sound to be 75 recorded.

By means of the auxiliary voltage supply circuit here shown and described and in which the voltage is supplied from the auxiliary amplifier 23 an additional amount of current is passed 80 through the galvanometer but only when sounds above a certain threshold of intensity are being delivered to the microphone. During all such intervals, therefore, the galvanometer is actuated to maintain the shutter 41 open. The instant, however, that the sounds delivered to the recording microphone cease or fall below a certain definite threshold value, no additional energy from the power amplifier or transformer 23 is delivered 85 to the large reservoir condenser 16, and as soon as the existing change in said condenser has cleared itself from the circuit, which it does by "tailing off" through the galvanometer circuit, and also including the resistance 14 and 20, the galvanometer returns to a normal state and closes the shutter 41. By properly selecting the value 90 of the capacity of the reservoir condenser 16 in series with the predetermined resistances 14 and 20 the time duration of the above mentioned "tailing off" can be controlled and thereby the actuation of the galvanometer is regulated so 95 that it will be quick to open the shutter 41 or to close the same at the beginning and end respectively of the recording action.

In Figure 3 of the drawing there has been illustrated another method by means of which 105 the galvanometer G' may operate a blade shutter 48, the galvanometer being connected through a lever 49 to the shutter 48 so as to positively oscillate the same across the slit 43' in a positive manner.

Various types of mechanism for operating the shutter may be employed, such for instance as a spring in combination with the galvanometer, or any sensitive electric motor, it being essential however that the galvanometer or operating 115 mechanism be so adjusted that the shutter is open the instant that sound is impinged upon the microphone, and closed the instant of the cessation thereof.

From the foregoing description taken in connection with the drawing, it is evident from this arrangement that the recording lamp may be actuated in its usual manner with the glow end thereof at the proper relative distance from the film, and that the sound recording operation 125 thereof is controlled in the usual manner while an auxiliary means is introduced and controlled through the action of the microphone so as to render the effect of the lamp upon the film effective or ineffective to produce what is known as 130 "noiseless recording".

What is claimed is:

1. A sound-on-film recording apparatus including in combination a film advancing means, means for directing a light beam to the film, a microphone, an amplifier the input of which is connected to the microphone, a power amplifier, the input of which is connected to the output of the amplifier, a second power amplifier connected to the output of the first amplifier, a 140 sound modulated recording lamp connected to the output of the first power amplifier, a rectifying network composed wholly of rectifying elements and connected to the output of the second power amplifier, a shutter interposed between the 145 recording lamp and the means for directing the light beam to the film, an electrical device operably connected to the shutter, a source of electrical energy connected to the output of the first amplifier and also to the output of the network; 150

and supplementing current source means maintained charged by means of the network whereby the output energy of the second power amplifier is at all times stored with current of unchanging polarity but in varying amounts at varying potentials, and whereby the shutter actuating electrical device is operated to hold the shutter closed when no sound is impinged upon the microphone, but to instantly open the same when

10 sound is impinged upon the microphone.

2. A sound-on-film recording apparatus as claimed in claim 1 wherein the electrical device is a galvanometer.

3. A sound-on-film recording apparatus as claimed in claim 1 wherein the electrical device is a galvanometer and the supplementing current source means is a reservoir condenser.

4. A sound-on-film recording apparatus as claimed in claim 1 wherein the electrical device is a galvanometer and the supplementing current source means is a reservoir condenser and the rectifying network is a Wheatstone bridge.

5. A sound-on-film recording apparatus including in combination a film advancing means, a fixed slotted barrier by means of which light is permitted upon a limited area of the film during the advancing thereof, a microphone, a first and second amplifier operably connected to the microphone, a first power amplifier connected to the output of the second amplifier, a sound modulated recording lamp adjacent the slotted barrier and operably connected to the output of the first power amplifier and the circuit thereto including a main source of electrical energy and a con-

denser, a galvanometer also connected to the output of the first amplifier and to the main source of energy and including in its circuit a condenser and a variable resistance, a second power amplifier in the form of a transformer connected to the output of the second amplifier, a Wheatstone bridge connected to the output of the transformer and having in circuit therewith a reservoir condenser, the latter of which is connected to the main electrical source of energy to constitute a supplementing current source means which is maintained charged by the Wheatstone bridge so that the output energy of the transformer is at all times stored with current of unchanging polarity but in varying amounts at varying potentials, and a shutter operably connected to the galvanometer to be interposed between the recording lamp and the slit of the slotted barrier whereby the same acts as a barrier to cut off the light from the recording lamp to the film when no sound is being impinged upon the microphone, and which is moved and held to open position during the impinging of sound upon the microphone.

6. A sound-on-film recording apparatus as claimed in claim 1, wherein the rectifying network is a Wheatstone bridge wherein the supplementing current source means is a reservoir condenser and wherein the electrical device includes a galvanometer coil and its armature with a shutter operably connected to the said armature and movable to either fully opened or fully closed position.
